UNITED STATES PATENT OFFICE.

GEORGE W. WEST, OF FAIRFIELD, IOWA, ASSIGNOR TO FRANK L. MCCLAIN, OF FAIRFIELD, IOWA.

BRUSH-HOLDER.

1,296,245.

Specification of Letters Patent.

Patented Mar. 4, 1919.

Application filed May 25, 1918. Serial No. 236,567.

To all whom it may concern:

Be it known that I, GEORGE W. WEST, a citizen of the United States, residing at Fairfield, in the county of Jefferson and State of Iowa, have invented certain new and useful Improvements in Brush-Holders, of which the following is a specification, reference being had therein to the accompanying drawings.

10 This invention relates to a brush holder, and has for its object the construction of a simple and efficient brush holder that comprises a minimum number of parts and which is efficient in operation and durable in 15 construction.

With this and other objects in view, the invention consists of certain novel constructions, combinations, and arrangements of parts, as will be hereinafter fully described 20 and claimed.

In the drawings:

Figure 1 is a top plan view of my improved brush holder, while

Fig. 2 is a view in side elevation of the 25 same.

Fig. 3 is a transverse sectional view taken on line 3-3, Fig. 2, and looking in the direction of the arrows.

Fig. 4 is a top plan view of the frame of 30 the holder.

Fig. 5 is a fragmentary, inverted, perspective view of the sliding plate carried by the frame.

Fig. 6 is a perspective view of the pivoted 35 jaw.

Fig. 7 is a fragmentary, longitudinal, sectional view of the brush holder.

Referring to the drawings by numerals, 1 40 designates the body of the frame, which is hollow, at 2, forming a socket into which a wooden handle 3 projects, which handle is, preferably, secured in the socket 2 by means of the rivet 4.

At the forward end of the frame is an 45 inwardly-extending integral hook 5 and between hook 5 and the socket portion 2 is a primary elongated slot 6 and an auxiliary elongated slot 7. The slot 6 is provided with a widened portion 8 for the purpose hereinabove described, and projecting into the slot 6 is a horizontal lug 9, which lug 9 is provided with an aperture 10. On each side of slot 6, in advance of the wide portion 8 are 50 parallel ribs or flanges 11. The inner end

of the slot 7 is closed by an integral transverse piece 12, Fig. 4.

The sliding plate 13 is provided, at its front end, with an integral transversely positioned jaw 14, which jaw 14 is comparatively wide and has a pair of gripping lugs 60 or teeth 15 upon its upper and lower edges.

Upon the plate 13 and near its middle, is a depending inclined lug 16 that extends through slot 7, and in the front of this lug 16 is formed notch 17, in which notch 17 is seated the eye 18 formed on the outer end of coil-spring 19; the inner end of the coil-spring 19 is provided with an eye, which is positioned in the aperture 10 of the inwardly-extending lug 9. 70

At the inner end of the plate, and on its under face, is formed a T-shaped tongue 21, the ends of which tongue extend under the parallel ribs 11, Fig. 3, assisting in holding the slideable plate 13 in an assembled position 75 upon the frame. Above the tongue 21 and in the plate 13 is formed a thumb-receiving socket or grip portion 22, Fig. 7.

Near the middle of the sliding plate 13 is formed an aperture 23 through which aperture 23 extends the bolt 24, which bolt also extends through slot 7 of the frame, as shown. 80

Upon the inner end of the bolt 24 is positioned a washer 25 and nut 26, for further 85 securing the sliding plate 13 upon the frame 1.

The auxiliary jaw 27 is provided with an extension 28 having an opening 29, in which opening 29 is positioned the hook 5 of the frame 1. The jaw 27 is provided with an upper and lower set of gripping lugs or teeth 15, the same as the fixed jaw 14. 90

Brushes having different width blocks 30, (Figs. 1 and 2) can be positioned between 95 the primary jaw 14 and the auxiliary jaw 27, and the positioning is accomplished by the operator gripping the handle and causing a finger or thumb to rest in the socket 22, pushing the sliding plate 13 forwardly upon 100 the frame 1 to allow the placing of the block 30 of the brush between the jaws, and more particularly between the lugs 15 of said jaws, as shown clearly in Fig. 2. Then upon 105 the operator disengaging the socket 22 of the sliding plate 13, the spring 19 will draw the sliding plate inwardly, causing the jaws to securely clamp the brush, thereby retain-

ing it in its assembled position upon the brush holder as long as the operator desires. To remove the brush, all that is necessary is to slide the plate 13 forward, sufficient manual strain being exerted to overcome the resistance of spring 19, thereby releasing the brush and permitting the same to be entirely removed from between the jaws, and then upon manual strain being removed from the 10 sliding plate 13, the spring 19 will draw the plate 13 inwardly upon the frame, closing the distance between the primary and auxiliary jaws and leaving the device free for quick adjustment for placing a brush between the jaws when it is desired to use the device.

I wish it to be understood that I reserve the right to make such alterations and changes to my invention as will be obvious 20 to one skilled in the art to which this invention relates, and which alterations and changes shall fairly fall within the scope of the appended claims.

What I claim is:

25 1. In a device of the class described, the combination of a frame provided at one end with a hook, a sliding plate carried by said frame, said plate provided at its outer end with a jaw, a pivotally-mounted jaw carried 30 by said hook, and means carried by said frame and normally exerting an inward pull upon said plate.

35 2. In a device of the class described, the combination of a frame provided at one end with a handle socket and at its opposite end with a hook, a plate slidably mounted upon said frame, means for retaining said plate in an assembled position upon said frame, said plate provided at its outer end 40 with a jaw, a second jaw pivotally mounted upon the hook of said frame, said frame provided with a lug, said plate provided with a lug, and a spring positioned between said lugs and attached thereto for normally exerting an inward pull upon said sliding plate.

45 3. In a device of the class described, the combination of a frame provided at one end with a handle-receiving socket and at its 50 opposite end with an inwardly-curving hook, said frame provided between said hook and socket with primary and auxiliary elongated slots, said frame provided with a pair of parallel ribs extending into said primary slot and also provided with a lug extending 55 into said primary slot at one end thereof, said primary slot being enlarged contiguous

to said lug, a sliding plate positioned upon said frame, said plate provided at its outer end with an integral jaw, said jaw being 60 comparatively broad and provided with an upper and lower set of brush-gripping lugs, said plate provided at its inner end on its upper face with a thumb socket and with a T-shaped extension under said socket, said 65 T-shaped extension being adapted to be positioned through the enlarged portion of the primary slot of the frame and having its ends positioned under the parallel ribs, said plate provided near its middle with an inclined depending extension and with an aperture, fastening means extending through the aperture of said plate and through the auxiliary aperture of said frame for assisting in securing the plate and frame together, 70 said inclined extension provided with a notch, a coil-spring fastened at one end in the notch of the inclined extension and at its opposite end in the aperture of the inwardly-extending lug of the frame, a jaw 75 provided with an apertured extension movably mounted in the hook of said frame, and said last-mentioned jaw being comparatively wide and provided with an upper and lower set of brush-gripping lugs.

80 4. In a device of the class described, the combination with a frame, of a plate slidably mounted upon said frame, a jaw fixedly secured to said plate, a second jaw pivotally mounted upon said frame, each 85 jaw being comparatively broad and provided with an upper and lower set of lugs, and means for retaining said plate and frame in an assembled position.

90 5. In a device of the class described, the combination of a frame provided with a jaw, a plate mounted upon said frame and provided with a jaw, said plate provided with a depending extension, said frame provided with an apertured lug, and a spring secured at one end to said extension and at 95 its opposite end to said lug for exerting an inward pull upon the plate.

100 6. In a device of the class described, the combination of a frame provided with a slot and a pair of ribs extending into said slot, a plate provided with a T-shaped extension having its ends positioned under said ribs, means carried by said frame and plate for exerting an inward pull upon the plate, and 110 jaws carried by said frame and plate.

In testimony whereof I hereunto affix my signature.

GEORGE W. WEST.
